Primary Examiner—Philip S. Hyder*Attorney, Agent, or Firm*—Chernoff, Vilhauer, McClung & Stenzel**[57] CLAIM**

The ornamental design for a folding scissors for a multi-purpose tool, as shown and described.

DESCRIPTION

FIG. 1 is a side view of a folding scissors for a multi-purpose tool, showing my new design;

FIG. 2 is a side view of the opposite side of the scissors from that shown in FIG. 1;

FIG. 3 is a top plan view thereof;

FIG. 4 is a bottom plan view thereof;

FIG. 5 is a rear end elevational view thereof;

FIG. 6 is a front end elevational view thereof; and,

FIG. 7 is a perspective view thereof, taken from a point above and ahead of and on the side of the scissors shown in FIG. 1.

The broken lines depicting the handle of the multi-purpose tool are for illustrative purposes only and form no part of the claimed design.
